UNITED STATES PATENT OFFICE.

CARL BORNMANN, OF BINGHAMTON, NEW YORK, ASSIGNOR, BY MESNE ASSIGNMENTS, TO AGFA ANSCO CORPORATION, OF BINGHAMTON, NEW YORK, A CORPORATION OF NEW YORK.

PLATE HOLDER

Application filed May 18, 1926, Serial No. 103,872. Renewed March 8, 1929.

My invention is directed to photographic sensitized plate or film holders, and will be referred to hereafter in the specification and claims as a plate holder. It will be understood however, that such reference is intended to include film holders as well.

As is well known, the usual plate holder is provided at one end with a hinged flap or gate member which serves the combined purpose of permitting access to the frame, whereby the plates may be placed therein, and also that of so closing the lower end of the frame after the sensitized plate has been placed therein, that actinic light is effectively locked out of said frame. To this end, the hinged flap is ordinarily formed to overlap the lower ends of the side pieces of the holder frame, and is also provided with a groove for receiving the lower end of the dark slide, when the flap is in closed position, whereby the same may be so held.

The difficulty of such construction, however, lies in the fact that at the points of overlapping between the hinged flap and the frame members, there are necessarily cracks and crevices which, unless very tightly closed, are apt to admit light through the frame to the plate in the holder. This is particularly true in the case of holders provided with springs for normally forcing the plate outwardly into the proper focal plane. The constant outward pressure of the spring and plate have a tendency to open the hinged flap so that upon the withdrawal of the dark slide, or if the flap happens to be a loosely fitting one, the flap may be forced open a slight distance, thus permitting light to enter around the overlapping edges and expose the plate or film. It is the purpose and principal object of my invention to provide a means for securing the flap in its closed position by a means which simultaneously covers the points of overlapping between the flaps and frame, thereby preventing any possibility of light leaking therethrough. I thus provide a better insurance against the leakage of light, first by positively preventing the opening of the flap by the pressure of the spring or plate within the holder, and secondly, by completely covering all of the joints, cracks, crevices and overlapping points between the flap and the frame, which constitute the weak points of the holder of today.

An understanding of the manner in which

I accomplish these results, may be had by reference to the accompanying drawing wherein like reference numerals indicate like parts.

In the drawing:

Figure 1 is a perspective view of my improved plate holder showing the hinged flap in its open position, and illustrating clearly the securing means therefor.

Figure 2 is a front plan view of the holder with the flap closed, and the securing devices or catches ready to be closed.

Figure 3 is a detail of one corner of the frame showing the flap closed and the catch in its securing position.

Figure 4 illustrates a modified form of the catch, and is a detail figure similar to Figure 3.

I have illustrated my invention in connection with the usual type or form of plate holders, which comprises the frame including side pieces 1 and 2, end pieces 3, and the flap 4 hinged to the bottom of the frame in any suitable manner, as by a cloth hinge indicated at 5. As is well known, the frame of the holder is provided with a partition or septum 6, extending between the frame pieces 1 and 2, and the end pieces 3, centrally thereof, thus dividing the frame into two compartments, one on either side of the partition 6. In each of the compartments, the side frame members 1 and 2 are provided with the grooves 7 and 8, the former adapted to receive the plate or cut film, and the latter to receive the ordinary dark slide 9, which permits the carrying of the holder in daylight without fogging the plate. The free edge of the flap 4 is provided with a recess 10 into which the lower edge of the dark slide 9 may engage when the flap is closed, as shown in Figure 2, and the slide is pushed downwardly its full length.

The lower end piece 3 of the frame is shouldered as at 11, and the flap 4 is similarly shouldered as at 12, whereby a comparatively light lock is formed between these two elements when the flap is closed. It will also be noted from Figure 1, that the frame members 1 and 2 are cut away as at 13 at their lower ends to receive the overlapping ends of the flap 4, and whereby the outer surface of the flap will occupy substantially the same plane as the outer surface of the frame pieces 1 and 2. This, of course, is for the conven-

ience in sliding the holder in and out of a camera. It will also be noted with reference to Figure 1, that the flap is provided adjacent its end with shoulders 14 which engage just inside of the frame pieces 1 and 2 when the flap is closed. This is to furnish an additional light lock. A spring 15 may be secured to the partition or septum 6, centrally thereof, to exert a tension outwardly whereby the varying width of the plates which are used in the holder may be compensated for by pressing said plates outwardly to the limit of their movements, whereby the plates are held in the proper focal plane.

15 It will be understood that the plate holder just described is provided with the identical construction shown in Figure 1 on the opposite side also, making it possible to carry two plates in the holder. Inasmuch as the construction of both sides is identical, it is deemed necessary to show and describe only one of them.

As before stated, the weak points in the construction so far described, lies in the fact that the shoulders 11, 12 and 14 as well as the ends of the flap which overlap the cutaway portions 13 of the frame, are not always tight fitting, or become loose, or shrink, or are opened slightly by the outward pressure of the spring 15 on the plate, thereby admitting light around such shoulders to the plate. To overcome this difficulty and to at the same time provide a means for securely holding the flaps tightly closed, and for covering the exposed joints and points of overlapping, I have provided each of the frame members 1 and 2 with the pivoted catches 16. These catches are pivoted at one end as at 17 to the sides of the frame members 1 and 2, and are provided at the opposite end with the embracing flanges 18 adapted to fit over the ends of the flaps 4, when in exposed position, and when so fitted to cover the points of overlapping between the flap and the frame. The frame members 1 and 2, and the flap 4, are cut away as at 19, to a depth equal to the thickness of the material of the catches 16, whereby the outer surface of the catches will lie in the same plane as the outer surface of the holder.

50 Figure 4 shows a modified form of catch 20 pivoted at 21, and which differs from the catch 16, only in that it is the same width as the frame member 2^a and may be of the length shown in Figure 4, or extend completely down to the end of the frame member and flap as shown in dotted lines at 22. There is some advantage in this type of construction over that shown in Figure 1, in that the cut away portion 23 extends completely across the frame and is thereby easier to form than the cut away portion 19 of the modification shown in Figure 1.

In the operation of the holder, the dark slide 9 is first removed, the catches 16 raised

to the position shown in Figures 1 and 2, the flap 4 pivoted downwardly, and a plate slipped into the holder guided in the groove 8. The flap 4 is then closed, the dark side 9 inserted, and the catches 16 pivoted downwardly to the position shown in Figure 3. The holder is then ready for use in the camera, or for carrying about until ready for use, without danger of light leaking past the joints between the flap 4 and the frame of the holder, and spotting the plate or film.

75 Many changes in details of construction and operation may be made without departing from the spirit of the invention. I do not limit myself therefore to the exact form shown and described other than by the appended claims.

I claim:—

1. A plate holder comprising a frame provided with grooves for receiving a plate and a protecting slide located therein, a hinged flap at one end of said frame permitting access to said grooves, and means independent of said slide movably mounted on said frame for engaging the ends of said flap and securing the same in closed position.

90 2. A plate holder comprising a frame provided with grooves for receiving a plate and a protecting slide located therein, a hinged flap at one end of said frame permitting access to said grooves, said flap also providing a light lock for said plate, and means independent of said slide movably mounted on said frame for securing said flap in closed position and for covering the points at which said flap and frame overlap.

95 3. A plate holder comprising a frame provided with grooves for receiving a plate and a protecting slide located therein, a hinged flap at one end of said frame permitting access to said grooves, said flap being shouldered and overlapping said frame to provide a light lock for said plate, and catches pivoted to said frame for embracing the ends of said flap to hold the same in closed position and to cover the points of overlapping between said flap and frame.

100 4. A plate holder comprising a frame provided with grooves for receiving a plate and a protecting slide located therein, a hinged flap at one end of said frame permitting access to said grooves, said flap being shouldered and overlapping said frame to provide a light lock for said plate, catches pivoted to said frame adjacent said flap and adapted to embrace the ends of said flap when in closed position whereby to secure it in such position and cover the points of overlapping between said frame and flap, said frame and flap being cut away to receive said catches whereby the outside surfaces of said frame, catches and flap lie in substantially the same plane.
